(57) **CLAIM**

The ornamental design for a planter harness, as shown and described.

DESCRIPTION

FIG. 1 is a perspective view of a planter harness showing my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view of a planter harness shown in use;

FIG. 9 is a front elevation view thereof;

FIG. 10 is a rear elevation view thereof;

FIG. 11 is a top plan view thereof;

FIG. 12 is a bottom plan view thereof;

FIG. 13 is a right side elevation view thereof; and,

FIG. 14 is a left side elevation view thereof.

The broken lines in the figures are for the purpose of illustrating portions of the planter harness and form no part of the claimed design. Additional broken lines in the figures showing the post and flowerpot illustrate environment and form no part of the claimed design.

1 Claim, 10 Drawing Sheets
